US00D598712S

(12) **United States Design Patent**
Alviar et al.

(10) **Patent No.:** US D598,712 S
(45) **Date of Patent:** ** Aug. 25, 2009

(54) **MUG**

(75) Inventors: **Christopher G. Alviar**, Seattle, WA (US); **Josh Kornfeld**, Seattle, WA (US); **Stuart Francis Ottenritter**, Phoenix, MD (US)

(73) Assignee: **Pacific Market International, LLC**, Seattle, WA (US)

(**) Term: **14 Years**

(21) Appl. No.: **29/302,061**

(22) Filed: **Jan. 9, 2008**

(51) **LOC (9) Cl.** 07-01

(52) **U.S. Cl.** D7/510; D7/511; D7/533

(58) **Field of Classification Search** D7/507, D7/509, 510, 511, 523, 533, 536, 532, 529; 220/703, 602; 206/457

See application file for complete search history.

(57) **CLAIM**

The ornamental design for a mug, as shown and described.

DESCRIPTION

FIG. 1 is a top right side perspective view of a mug showing our new design;

FIG. 2 is a rear elevational view thereof;

FIG. 3 is a front elevational view thereof;

FIG. 4 is a left side elevational view thereof, the right side elevational view being a mirror image thereof;

FIG. 5 is a top plan view thereof;

FIG. 6 is a bottom plan view thereof;

FIG. 7 is a top right side perspective view of a second embodiment thereof;

FIG. 8 is a rear elevational view thereof;

FIG. 9 is a front elevational view thereof;

FIG. 10 is a left side elevational view thereof, the right side elevational view being a mirror image thereof;

FIG. 11 is a top plan view thereof; and,

FIG. 12 is a bottom plan view thereof.

The broken lines are for illustrative purposes only and form no part of the claimed design.

1 Claim, 10 Drawing Sheets
